STRAIGHTENING MACHINE

Fritz Ungerer, Pforzheim, Germany

Application May 19, 1937, Serial No. 143,467
In Germany October 5, 1936

3 Claims. (Cl. 153—54)

The present invention relates to sheet straightening machines or roller levelers and more particularly to a balanced supporting means for the straightening rolls.

An object of the present invention relates to automatically displacing the ends of the straightening rolls in a direction opposite to the movement thereof at another point upon which pressure has been applied.

In the straightening of sheets or plates it is, under certain conditions, necessary to apply a greater pressure to the center of the sheet without effecting a stretching at the ends thereof. The machines now in use, while being able to apply a greater pressure to the center of the sheet and independently adjust the ends of the straightening rolls, do not provide means for adjusting the ends of the straightening rolls simultaneously with the movement given to the center portion thereof to give a wider space between their bearing centers to eliminate the possibility of stretching the edges of the sheet when it is not desired. However, under the present invention, the disadvantages of the prior art are overcome and it is possible to simultaneously adjust the ends of the straightening rolls upon their opposite movement at another point between the ends thereof.

Other objects and advantages will become apparent as the description proceeds, in which:

Figure 1 is a sectional elevational view showing the deflection of the straightening rolls and displacement of the bearing supporting means;

Figure 2 is a section on the line II—II of Figure 1;

Figure 3 is a detailed section showing one manner of effecting a simultaneous movement of the bearing housing upon vertical movement of the center supporting rollers;

Figure 4 is an end elevation of a straightening machine showing the arrangement of the balancing yokes;

Figure 5 is a section on the line V—V of Figure 4;

Figure 6 is a sectional elevation of a modified form of balancing yoke;

Figure 7 is a detail view of a form of construction to permit movement of the bearing housing on the frame independent of the movement of the center portion of the straightening rolls; and

Figure 8 is a detail showing of the balancing yoke mounting means to permit adjustment of the pivotal point to increase or diminish the lever arm effect.

In the drawings, the numerals 1 and 2 repre-

sent upper and lower straightening rolls of a straightening machine or roller leveler. The ends of said straightening rolls 2 are suitably supported in bearing housings 3 carried by bearing supporting members 4. The bearing supporting members 4 are provided with threaded portions 5 adapted to engage the internal threaded portions of nuts 6 which are journaled or otherwise secured to the machine standard 7.

Suitably mounted in said machine standard 7 are nuts 8 having an internal threaded portion adapted to receive threaded portions 9 of the spindles 10. The spindles 10 are adapted to carry, in any desired manner, at least one supporting roller 12 journaled in a housing 13.

The bearing supporting members 4 are each provided with a worm gear 14, while the spindles 10 are provided with a worm gear 15. These gears 14 and 15 are adapted to mesh with worm gears 16 and 17 carried by a shaft 18 suitably journaled in the machine frame and upon which is mounted, in any desired manner, a hand-wheel 19.

When it is desired to move the lower straightening roll 2 out of its normal horizontal plane, the hand-wheel 19 is rotated to drive the worm gears 16 and 17 which mesh with worm gears 14 and 15 and effect simultaneous vertical movement of the bearing supporting members 4 in a direction opposite to the movement of the spindles 10. In other words, if the spindles 10 move upwardly, the bearing supporting members 4 simultaneously move downward. Such an operation is effected by providing the threaded portions 5 and 9 or the worm gears 14 and 15 with different directions of travel. For example, if the spindles 10 or the worm gear 15 have right-hand threads, then the bearing supporting members 4 or the worm gears 14 should have left-hand threads. However, should it be desired to have the spindles 10 move up or down to a greater extent than the simultaneous movement in an opposite direction of the bearing supporting members 4, such a movement may be effected by providing the threaded portions 5 of the members 4 and the threaded portions 9 of the spindles 10 with a different pitch, or through a different ratio of the worm gears 15 and 16.

By referring to Figure 1, there is shown a working pressure applied to the center portion 50 of said straightening rolls 2 to react upon the sheet of material R passing therethrough. In this position there is a distance e_1 between the upper and lower straightening rolls at their center portions and, due to the simultaneous down-

ward movement of the end bearings 3 upon the upward movement of the central portion of said straightening rolls, there is a distance e_2 at the end bearings.

- 5 The bearing housings 3 are connected to the bearing supporting members 4 as shown in detail in Figure 3. Under such a construction, when the spindles 10 are raised to flex the straightening rolls at their center, said straightening rolls 10 2, together with their bearing housings 3, are supported entirely by the supporting rollers 12. However, since the bearing supporting members 4 move simultaneously in a direction opposite to the movement of said spindles 10, they will be lowered away from the bearing housings 3. Therefore, said bearing housings 3 can be displaced from their normal horizontal plane at any time by the pressure exerted upon them by the sheet of material R for the width X, as shown in Figure 1. This movement is in a direction opposite to the direction of the working charge upon the sheet of material and, therefore, no working charge is effected upon the edges of the sheet material.

- 20 Referring to Figures 4 and 5, the machine standard 7 is provided with the usual side frames 20 for supporting the straightening rolls 1 and 2, the latter rolls 2 being positioned in a frame 21.

The machine standard 7 is provided with two raised portions 22 and a lowered or intermediate portion 23. The raised portions 22 are provided with upstanding ears 24 to receive a pin 25 for pivotally supporting balancing yokes 26. These balancing yokes 26 are provided with upstanding bearing supports 27 between which are positioned relatively short supporting rollers 28 adapted to support the straightening rolls over approximately their entire length. The balancing yokes are pivotally supported in a plane transverse to the length of the straightening rolls in order to permit said balancing yokes to oscillate over the longitudinal area of said straightening rolls.

The balancing yokes 26 are each provided with a lateral extension 29 on an end adjacent each other, as more clearly shown in Figure 5. The extension 29 is formed on the front of one yoke and the back of the adjacent yoke in order to overlap one another and be secured in position for simultaneous vertical movement, as shown in Figure 4. Each extension 29 is provided with an opening 30 within which is positioned a bearing 31 to support a stub shaft 32 having a depending screw spindle 33. In threaded engagement with the screw spindle 33 is a worm gear 34 adapted to mesh with a worm 35 carried by the shaft 36. The shaft 36 is mounted in suitable bearing members on the machine standard and is provided on one end with a hand-wheel 37 adapted to rotate said gears 34 and 35 to move the abutting ends of said balancing yokes 26 vertically.

The ends of the balancing yokes adjacent the side frames 20 of the machine are provided with arcuate surfaces 46 upon which rest the arcuate surfaces 47 of the straightening roll frames 21. Pivotally secured to the straightening roll frames at 38 and to the balancing yokes at 39 are plates or links 40 adapted to form a cooperating connection between the frames 21 and balancing yokes 26 so as to permit the frames 21 to pivot about the connection 38 when a movement is effected between the arcuate bearing surfaces 46 and 47.

However, it may not be desired to lower the ends of the straightening rolls simultaneously with the raising of the middle or center portion

of said straightening rolls. Therefore, the plates 40 may be omitted and the pivotal connection 38 between the straightening roll frames and the balancing yokes 26 may be positioned in slots 41 formed in the side frames 20. Such an arrangement would not simultaneously displace the bearing ends of said straightening rolls downwardly when the center portion of said straightening rolls was moved upwardly vertically, but would leave said bearing ends to be displaced from their normal horizontal plane in a direction opposite to the working charge pressure applied at the center of said straightening rolls upon the pressure of the sheet material passing through the machine. By such a construction, the bearing end portion of said straightening rolls will not exert an effective working charge pressure upon the edges of the sheet.

By raising or lowering the screw spindle 33 upon rotation of the hand-wheel 37, the balancing yokes 26 operate in unison and oscillate on their pivotal connections 25 in the direction of the longitudinal axes of the straightening rolls. As the screw spindle is rotated to raise the pivotally connected ends of adjacent balancing yokes 26 to raise the supporting rollers 28 for exerting a pressure upon the straightening rolls in their center portion, said straightening rolls assume a position similar to that shown in Figure 1 and, in so doing, the bearing ends of said straightening rolls positioned within said frames 21 simultaneously lower and effect a slight swiveling around the pivotal connection 38 and relieve said pivotal connection 38 of the strain on the bearing ends due to the flexure of said straightening rolls. This lowering movement of the frames 21 is similar to the lowering of the bearing housings 3, the width of such lowering being indicated at X in Figure 1.

If the balancing yokes 26 are of the same size, then the distance the spindle 33 is raised and the frames 21 lowered will be equal. A variation in the distance that the screw spindle 33 is raised and the frames 21 lowered can be obtained by varying the size of the balancing yokes 26. In any event, the size of the balancing yokes are chosen in such a way that with the upward vertical movement thereof to raise the straightening rolls at their center portion, the frames 21 simultaneously lower so that the effective working charge is obtained in the center of the sheet being straightened while the ends of said straightening rolls have no effective pressure upon the sheet. If desired, the pivotal mounting point of the balancing yokes may be made adjustable along the longitudinal axis of the straightening rolls by providing any well known and usual adjustable mounting as, for example, the pins 25 may be mounted for adjustment in bearing slots in the yokes 26, whereby the lever arm effect of the yokes on the opposite sides of the pins 25 may be increased or diminished.

In Figure 6, a modified form of balancing yoke 26 is shown. In this construction, the pivotal support 25 is connected to the machine standard 65 the same as described in Figures 4 and 5, while the upper portion of said yoke is cored out to provide pockets adapted to pivotally receive frames 43 on which are mounted individual supporting rollers 28. These frames 43 are pivotally mounted at 44 on the upper portion of said yokes and provided with semi-cylindrical surfaces 45 adapted to oscillate around said pivot 44 in said pockets formed in the upper portion of said yoke and thereby permit the supporting rollers 28 to 75

adapt themselves to the deflection curve assumed by said straightening rolls when said balancing yokes have been adjusted through the movement of said screw spindle 33.

5 While I have shown and described specific embodiments of the present invention, it will be understood that I do not wish to be limited exactly thereto, since various modifications may be made without departing from the scope of the
10 invention as defined by the following claims.

I claim:

1. In a roller leveler, straightening rolls, supporting means for said straightening rolls and means for simultaneously moving said straightening rolls and supporting means out of their normal horizontal plane, said second named means comprising balancing yokes pivotally supported on said leveler and having their inner ends pivotally connected together with the other ends
15 20 swiveled to said supporting means.

2. In a roller leveler, straightening rolls, supporting means for said straightening rolls and

means for simultaneously moving said straightening rolls and supporting means out of their normal horizontal plane, said latter means comprising balancing yokes having their inner adjacent ends pivotally connected together with the other ends swiveled to said supporting means, said supporting means having their ends mounted on a balancing yoke for swivel movement.
5

3. In a roller leveler, straightening rolls, supporting rollers for said straightening rolls, bearing supports for the ends of said straightening rolls, said supporting rollers mounted in balancing yokes, means for pivotally connecting the bearing supports of said straightening rolls to said balancing yokes for pivotal movement between said members and means adapted to move the center portion of said straightening rolls out of its normal horizontal plane, the ends of said straightening rolls adapted to be simultaneously moved in an opposite direction.
